UNITED STATES PATENT OFFICE.

ALVAH F. LENT, DECEASED, BY IDA HAWKINS-LENT, OF EAST ORANGE, NEW JERSEY,
ADMINISTRATRIX, AND ALVAH D. LENT, OF NEWARK, NEW JERSEY.

TOY PARACHUTE.

Application filed October 7, 1927. Serial No. 224,598.

The object of the invention is to provide a toy comprising a parachute and housing means therefor for condensing the whole into small compass to be cast into the air; to provide the housing means with a locking element releasable after an interval of time, so that the housing means may be opened to release the parachute; and to provide a casting member with which the housing means detachably connects, so that the device may be readily thrown into the air.

With this object in view the invention consists in a construction and combination of parts of which a preferred embodiment is illustrated in the accompanying drawings, in which:

Figure 1 is a side elevational view of the toy in extended or operative position.

Figure 2 is a similar view showing the housing means closed and the parachute enclosed thereby.

Figure 3 is a central vertical sectional view through the structure shown in Figure 2 but with the casting means attached.

Figure 4 is a detail elevational view illustrating the hinge connection between the elements of the housing means.

The housing means or container 10 is of hollow spherical form and is composed of complementary elements 10^a and 10^b consisting of hemispheres hingedly connected as at 11 and yieldingly impelled to open position by means of springs 12 operatively connected with the hinge. The parachute 14 has its guy ropes 15 connected with the container at the hinge and is of a size, so that when collapsed, it may be completely enclosed together with the ropes by the container when the hemisphere 10^a is swung over on the hemisphere 10^b.

Diametrically opposite the hinge each hemisphere is provided with a radial peg or stud 16 to one of which is anchored one terminal of a cord 17 carrying at its free end a small weight 18. In the closed position of the container, the cord is wrapped around the two studs 16 and thus maintains the con-

tainer in closed position against the action of the spring 12.

Disposed at an angular distance of 90 degrees from the hinge 11, the hemisphere 10^b is provided with a socket 19 engageable with a head 20 formed at the extremity of a casting element 21. The head 20 engages loosely in the socket and the latter is adapted for the reception of an explosive cap on which the head bears. The operation of striking the bent or curved portion of the handle against the pavement serves to explode the cap and the container is thus cast into the air.

When at rest, the cord 17 maintains the container in closed position but upon the latter being thrown into the air, the swinging movement imparted to the weight 18 unwinds the cord from the peg or stud 16 until finally the spring 12 is free to act and the container is swung to open position such as indicated in Figure 1, when the parachute is released and, opening, permits the device to settle gradually to the ground.

The container may be constructed with the cup 19 omitted, when the device is then cast merely by throwing it into the air from the hand.

The invention having been described, what is claimed as new and useful is:

A toy of the kind described comprising a container consisting of hingedly connected complementary elements normally impelled to open position, a parachute connected with the container at the hinge connection between the elements and housed by the latter when closed, and a time-governed locking means for the container comprising a weight-actuated cord wrapped around pegs on said complementary elements diametrically opposite the hinge.

In testimony whereof they have affixed their signatures this 13th day of March, 1928.

ALVAH D. LENT.

IDA HAWKINS-LENT,
Administratrix of the Estate of Alvhah F.
Lent, Deceased.
